11 Claims

ABSTRACT OF THE DISCLOSURE

The ash receptacle comprises a stamped sheet metal housing structure which slidably receives and houses a stamped sheet metal ash box or tray. The mounting structure is in the general form of an inverted U-shaped housing, which is suitably affixed rigidly within the dashboard of an automobile, behind the latter's instrument panel; and this mounting structure carries an elongated non-metallic integral one-piece guide unit on each of its parallel, laterally spaced and depending side walls. Each guide unit includes a pair of elongated, generally vertically spaced guide or rail members which are connected together at longitudinally spaced points by a plurality of relatively thin resilient or spring-like elements. The uppermost rail member is fixedly secured to the inner surface of a side wall of the mounting structure while the lowermost member, with the tray removed, is free to move, the amount of movement depending to some degree upon the flexibility and construction of the resilient elements.

For coaction with the resilient elements on the mounting structure, the ash box has an elongated, metallic and one-piece guide mounted on the outer surface of each of its upright side walls, in a longitudinal zone laterally paralleling that of the guide units of the stamped mounting member. When the component parts of the ash receptacle are assembled the resilient elements urge the lowermost rail or guide member downwardly away from the uppermost rail member to insure a tight or snug fitting engagement between the corresponding guide and guide unit. The guide units are of molded nylon or other moldable plastic material known for its low co-efficient of friction in sliding engagement with a metal member. As an example, the guide units may be made from Delrin 900. The rail or guide members on either side of the mounting structure are formed on their upper and lower surfaces with a V-outline for a slidingly guiding engagement with mating formations integral with the metallic guide of the ash box.

CROSS REFERENCE TO RELATED APPLICATION

The improvements of the subject ash tray constitute a simplification of structural features illustrated and described in the copending application of Jack W. Blake entitled "Ash Receptacle for Automobiles," Ser. No. 682,453, filed Nov. 13, 1967, and assigned to the assignee of record. The receptacle of that application includes a pair of metallic guide units, each unit being made from three parts including a pair of elongated die cast members having a sinuous or undulatory wire spring acting therebetween to bias the lowermost die cast member downwardly away from the uppermost die cast member, the latter being fixedly secured to the inner surface of a side wall of the mounting structure. In contrast, the present receptacle includes a pair of integral one-piece guide units, each unit including a single plastic body which supersedes the two die cast parts and spring required in the aforementioned application.

2

BACKGROUND OF THE INVENTION

Field of the invention

As appears above, the ash receptacle is designed for automotive use in the familiar environment of the vehicle's dashboard. Quite likely, however, its improved features in point of structural simplicity, low friction operation, low cost and the like, will recommend the structure for other applications.

10

Description of the prior art

I am aware of no prior art disclosures more pertinent in nature than that of the aforementioned Blake copending application and the patent to Blake, No. 3,355,232 of Nov. 28, 1967, which also discloses the feature of a two-part die cast guide unit, the parts of which are vertically biased away from one another, as by an elongated, mildly undulatory wire spring, for sliding action between non-metallic guide formations. The patents to Middleton No. 3,109,688 of Nov. 5, 1963, and Middleton et al. No. 3,285,683 of Nov. 15, 1966, show ash receptacles comprising mounts and boxes generally similar as to proportion and size alone to the present receptacle; but they involve roller-type guide means having no pertinence to the type of guide arrangement herein contemplated. Hendricks 2,334,925 of Nov. 23, 1943, discloses a slide type of guide for an automotive ash receptacle, but lacks features of improvement of the slide means or units mentioned in the abstract.

Otherwise, certain patents directed to drawer slides, such as Pratt No. 2,265,927 of Dec. 9, 1941, Miller No. 3,059,986 of Oct. 23, 1962 and Barnes No. 3,092,429 of June 4, 1963, illustrate the use of elongated slide guide means for a drawer or the like. None of the above, however, involves an integral non-metallic guide unit on one box or mount component and a coacting metallic guide member on the other component.

40

SUMMARY OF THE INVENTION

The receptacle of the invention comprises an assembly of an ash box or tray of rather conventional configuration slidably and removably associated with a dashboard mount, also of more or less known configuration. One of these members, illustrated herein as being the box, has an inexpensive elongated metallic guide of generally channeled or C-shaped cross-section secured to each outer side thereof. However, these metallic guide members might also be applied to the inner side walls of the mounting structure, if deemed desirable. As actually shown, the mounting structure has a one-piece guide unit including integral resilient elements on each of its side walls; and the pair of guide units on the respective box sides are formed for sliding coaction between upper and lower lip portions of the metallic guide channels.

55 Otherwise, the present ash box carries the usual type of manually depressable spring retainer, by which the withdrawing motion of the box from the mount is limited, and upon depression of which a full separation of the box from its mount may be effected. In another respect, not germane to the present invention, the box is equipped with a decorative front escutcheon piece blending with the contour and appearance of the dashboard when the receptacle is closed.

60

BRIEF DESCRIPTION OF THE DRAWINGS

FIG. 1 is a side elevational view of the improved receptacle, with a near wall of its sheet metal mounting member of the latter broken away, as on line 1—1 of FIG. 4, to permit viewing its internal guide means;

70 FIG. 2 is a top plan view of the ash box of the receptacle taken on the line 2—2 of FIG. 1.

FIG. 3 is a side elevational view of the box, as seen from the direction of the arrow 3 of FIG. 2.

FIG. 4 is a transverse vertical view, partly in section, through the ash receptacle and taken on the line 4—4 of FIG. 1.

FIG. 5 is a front elevation of the integral, elongated, non-metallic guide unit.

FIG. 6 is a sectional view taken on the line 6—6 of FIG. 5.

FIG. 7 is a sectional view taken on the line 7—7 of FIG. 5.

FIG. 8 is a sectional view taken on the line 8—8 of FIG. 5.

As illustrated in FIGS. 1 and 4, the receptacle, generally designated by the reference numeral 10, is mounted behind the dashboard panel area of a vehicle by a generally inverted U-shaped mount or mounting structure, generally designated 12, which is suitably fastened by riveting, welding or equivalent means to the vehicle body structure, in a well known way not requiring illustration. Each of the parallel upright and laterally spaced walls 14 of the mount 12 carries an elongated, one-piece, non-metallic guide unit, generally designated 16, features of which will hereinafter be described in detail.

As for the ash box or tray 18 of receptacle 10, its configuration, including transversely spaced parallel and upright side walls 20, bottom 22, rear wall 24 and upwardly sloping front wall 26, is, as appears in FIG. 3, generally similar to existing ash box structures. FIG. 1 shows bottom wall 22 and front wall 26 as being equipped with an ornamental escutcheon piece 28 blending in contour and finish with the dashboard, which piece constitutes no part of the improvement.

Similarly, the rear wall 24 carries a forwardly projecting, leaf spring type retainer 30 by which outward withdrawal of the box 18 is limited and upon manual depression of which piece 30 the box 18 may be disengaged from mount 12 and withdrawn wholly for emptying. Further, front wall 26 has an integral, rearwardly disposed cigaret snub-out part 32 which, like spring member 30 and escutcheon 28 is not a feature of the invention. In general, mount 12 and box 18 are fabricated conventionally by stamping, with the union of certain margins or parts effected by riveting, welding or the like, all in accordance with accepted procedures in this art.

Referring particularly now to FIGS. 2, 3, and 4, each of the side walls 20 of the ash box 18 carries fixedly on its outer surface, in a zone parallel with and somewhat above its bottom 22, an elongated, one-piece metallic guide member 36 made, as an example, from cold rolled steel. The guide member 36 is shown as being rigidly affixed to the box side walls 20 by means of a plurality of rivets 38, although other means may serve the purpose. As best shown in FIG. 4, each of the guide members 36 is of a generally C-shaped cross-section, including an upright wall or body portion 40, which is brought by rivets 38 flush against the outer surface of box wall 20, and top and bottom lips 42, 44 defining a channel-like guide groove or way 46. FIGS. 2 and 3 show the guide members 36 as extending a major part of the front-to-rear length of the walls 20, terminating approximately at the rear box wall 24.

FIGS. 4—8 inclusive best show the structure of the guide units 16 attached to the inner sides of the two upright walls 14 of the mount or mounting structure 12. Each of these units 16 includes an upper rail or guide member 50 of elongated nature and being provided at the ends thereof with a pair of depending, relatively wide end legs integrally connected thereto. The guide unit 16 is secured to the mount wall 14 at the end legs 52, as by rivets 54 or equivalent means as shown in FIG. 1. A second integral part of the guide unit 16 is a lower elongated guide or rail member 56, shown as being a trifle shorter than the distance between legs 52 of the elongated upper rail or guide member 50.

The rail or guide members 50 and 56, save at the ends thereof, are of substantially the same vertical cross-section, as best appears in FIGS. 4 and 6, although oriented oppositely in the vertical sense. Thus, each has a vertically facing, V-shaped groove or channel 58 extending throughout its length. The upper and lower rail or guide members 50 and 56 of each guide unit 16 are spaced vertically apart and connected at their opposing inner surfaces 64 and 68 respectively by a plurality of resilient, spring-like elements or fingers 60. Specifically, four such resilient elements 60 are utilized including elements near the ends of the members 50 and 56 and at two intermediate spaced points as shown in FIG. 5. The resilient elements 60 are each arranged on a 30° angle and have a width of approximately .20" equal to the width of the rail members 50 and 56 as best shown in FIG. 7. The thickness of each element or finger 60 as represented by the letter X in FIG. 5 is .03". Thus the relatively thin elements or fingers 60 are constructed and arranged to exert an outward biasing force when the rail members 50 and 56 are urged together in the direction of arrows y—y of FIG. 5 when inserted in the channel of the corresponding guide 36 as shown in FIG. 4. The inside surface 64 of guide or rail member 50 is provided with a pair of downwardly extending protuberances 66 engageable with the inside surface 68 of rail or guide member 56 for limiting the members 50 and 56 to a predetermined minimum vertical spacing relative to one another.

Each guide unit 16 is molded in one piece from a suitable plastic material such as nylon or Delrin 900 or other non-metallic material having a desired limited frictional character in sliding engagement with metal. The integral guide unit includes all the functions previously performed by three separate parts as described in the aforementioned Blake patent application.

FIG. 4 shows the mounting and box members 12 and 18 as operationally assembled to one another. The upper and lower lips 42, 44 of the box-carried metallic guides 36 are received in the guide channels 58 of the respective rail members 50 and 56, and the latter are resiliently urged apart by the resilient elements 60 which are initially compressed when inserting such guide or rail members into the metallic guides 36. Sufficient friction is present to hold box 18 stably in a partially or wholly retracted position, yet the anti-friction nature of the guide units 16 permits smooth and easy shift of the box 18 in relation to the metallic guides 36.

What is claimed as my invention is:

1. A receptacle of the type described, comprising a fixed mounting member, a slidable box or like member adapted for sliding withdrawal and retraction movement relative to said mounting member, and means slidably connecting said members for said movement, comprising an elongated guide fixed on one of said members, and an integral elongated one-piece guide unit of a non-metallic material having a low coefficient of friction on the other, said guide providing aligned and spaced, longitudinally extending guideway portions, said integral guide unit comprising a first elongated guide component fixedly mounted on the other of said members and having a portion slidably engaging one of said guideway portions of said guide, a second elongated guide component in laterally spaced relation to said first component and having a portion slidably engaging the other guideway portion of said guide, and resilient means interposed between and integrally connecting and biasing said first and second elongated guide components relative to one another for sliding action of the respective portions of said guide components relative to the respective guideway portions of said guide.

2. The receptacle of claim 1, in which said guide is of C-shaped cross-section to provide mutually facing guideway portions, said guide unit components being slidably mounted in said guide and being of a cross-section affording V-shaped portions slidably engaged by the respective guideway portions of said guide.

3. The receptacle of claim 1 in which said resilient means comprises a plurality of relatively thin and flexible fingers interposed between opposing elongated surfaces of said first and second guide components.

4. The receptacle of claim 3 in which said fingers are longitudinally spaced apart and are located near the ends of said guide components and at one place therebetween.

5. A receptacle of the type described, comprising a fixed mounting member, a slidable box or like member adapted for sliding withdrawal and retraction movement relative to said mounting member, and means slidably connecting said members for said movement, comprising an elongated guide fixed on one of said members, and an integral elongated one-piece guide unit on the other, said guide providing aligned and spaced, longitudinal extending guideway portions, said integral guide unit comprising a first elongated guide component fixedly mounted on the other of said members and having a portion slidably engaging one of said guideway portions of said guide, a second elongated guide component in laterally spaced relation to said first component and having a portion slidably engaging the other guideway portion of said guide, and resilient means integrally connecting said biasing said first and second elongated guide components, relative to one another for sliding action of the respective portions of said guide components relative to the respective guideway portions of said guide, said guide being of C-shaped cross-section to provide mutually facing guideway portions, said guide unit components being slidably mounted in said guide and being of a cross-section affording V-shaped portions slidably engaged by the respective guideway portions of said guide, said guide being made from a metallic material and said integral guide unit being made from a plastic material, said resilient means comprising a plurality of relatively thin and flexible fingers interposed between opposing elongated surfaces of said first and second guide components, said fingers being longitudinally spaced apart and being located near the ends of said guide components and at at least one place therebetween, each of said fingers being inclined at approximately a 30° angle with respect to the longitudinal axis of the guide unit.

6. For use in association with an automotive ash receptacle, a guide unit comprising a one-piece elongated body made from a non-metallic material having a relatively low coefficient of friction, said body comprising a pair

of laterally spaced apart elongated guide components, and a plurality of relatively thin resilient elements connecting the opposing surfaces of said guide components and providing for relative lateral displacement between said guide components.

7. The guide unit defined in claim 6 in which said body is made from a plastic material.

8. The guide unit defined in claim 6 in which said resilient elements include elements near the ends of said guide components and at one place therebetween.

9. A guide unit for an ash receptacle comprising a one-piece elongated body made from a non-metallic material having a relatively low coefficient of friction, said body comprising a pair of laterally spaced apart elongated guide components, and a plurality of relatively thin resilient elements connecting the opposing surfaces of said guide components and providing for relative lateral displacement between said guide components, said resilient elements including elements near the ends of said guide components and at at least one place therebetween, said resilient elements being inclined at approximately a 30° angle with respect to the longitudinal axis of said body.

10. The guide unit defined in claim 9 in which the inner surface of one of said guide components includes means for limiting the relative lateral displacement between said guide components.

11. The guide unit defined in claim 10 wherein one of said guide components is longer than the other of said guide components and includes laterally extending mounting lugs at the ends thereof.
